CLAIM

The ornamental design for a exercise apparatus, as shown and described.

DESCRIPTION

FIG. 1 is a perspective view of our new exercise apparatus;
FIG. 2 is a front side elevational view of the exercise apparatus;

FIG. 3 is a rear side elevational view of the exercise apparatus;
FIG. 4 is a left elevational view of the exercise apparatus;
FIG. 5 is a right elevational view of the exercise apparatus;
FIG. 6 is a top plan view of the exercise apparatus; and,
FIG. 7 is another perspective view of the exercise apparatus.
The broken lines in the drawings depict unclaimed environmental subject matter.
